UNITED STATES PATENT OFFICE.

BENJAMIN HEYWOOD, OF BROOKLYN, NEW YORK, AND JOHN JONES, OF JERSEY CITY, NEW JERSEY.

HOSE-REEL.

SPECIFICATION forming part of Letters Patent No. 292,226, dated January 22, 1884.

Application filed May 22, 1883. (No model.)

To all whom it may concern:

Be it known that we, BENJAMIN HEYWOOD and JOHN JONES, respectively of Brooklyn and of Jersey City, in the counties of Kings 5 and of Hudson, and States of New York and New Jersey, have invented certain new and useful Improvements in Hose-Reels; and we do hereby declare that the following is a full, clear, and exact description thereof, reference 10 being had to the accompanying drawings, and to the letters of reference marked thereon, which form part of this specification.

Our invention relates to improvements in 15 hose-reels, in which means of obtaining a water-supply at any point within a given radius from a stationary source are provided for fire-extinguishing and other purposes; and the objects of our improvements are, first, to effect the opening and closure of the supply-valve 20 automatically by the rotation of the reel; second, to cause the valve to operate only when desired; third, to establish direct communication of the hose with the water-supply by making the shaft of the reel partially hollow; 25 and, fourth, to accomplish these ends with simplicity of construction, we attain these objects by the mechanism illustrated in the accompanying drawings, in which—

Figure 1 is a plan view of our invention, 30 partially broken and in section. Fig. 2 is an end elevation of the same. Fig. 3 is a detail section thereof, showing the means by which water is conducted to the hose on the drum of the reel and of controlling such supply; and 35 Fig. 4 shows the valve-operating mechanism.

Similar letters indicate corresponding parts throughout the views.

A A represent the bearings in which the journals B B of the shaft C, on which the reel 40 O is mounted, revolve. The journals B B are prolonged at one end to give a location for the crank R, suitably affixed thereto, and at the other end to afford a bearing, respectively, to the concentric disk E and to the cog-wheel D. The shaft C is partially hollow to permit the communication of water from the pipe L to the tube M. The cog-wheel D, when in contact with the toothed segment I, meshes therewith. The disk E, mounted on the shaft

C, has a lug or projection, F, on its circumference, which, during the revolution of said disk, engages either end of a slot, G', in the yoke G, according as the motion of the disk is forward or backward. The yoke G serves to disconnect or gear the segment I with the wheel D, thus effecting the operation of the supply-valve K, and is pivoted by an arm, H, to the headed segment I, mounted on the shaft K. Its slot G' is cut concentric with its own line of curvature, and the slot is so terminated by the walls of the yoke as to engage the lug F on the disk E at timed periods, whereby the shifting of the valve is accomplished. This yoke is elliptical in shape.

N is the drum on which the hose P is wound, 65 the inner end being connected to the pipe M, projecting through its surface, and the outer end to a suitable nozzle.

O is the frame-work of the reel. The operation is as follows: When water is 70 desired at any point, near or remote, the hose is unwound from the reel by merely pulling it, which act causes the revolution of the reel-shaft C, and hence of the disk E and cog-wheel D. In traversing its circuit the projection F on the disk E meets and engages the vertical wall of the slot G', and forces the yoke G to partake of its own motion, which forward motion of the yoke effects a corresponding forward motion of the crank-arm H, and conversely, thus alternately engaging and disengaging the geared segment I, and effecting the shifting of valve K. It will be understood 75 that the same means which suffice to turn on the water are equally efficacious in shutting it off, which is done in the same manner during the reverse motion caused by turning the crank R to rewind the hose on the drum.

Having thus fully described my invention, what I claim, and desire to secure by Letters 80 Patent of the United States, is—

1. In hose-reels, the combination, with the headed toothed segment I, having a yoke, G, pivoted thereto, of a disk, E, having a projection, F, on its circumference, a cog-wheel, 95 D, mounted on the same axis, partially hollowed shaft C, and valve K, substantially as and for the purpose specified.

2. In hose-reels, the combination, with the headed toothed segment I, having an elliptical yoke, G, pivoted thereto, disk E, having a projection, F, on its circumference, and cog-
5 wheel D, of valve K, operated as described, pipe L, tube M, and shaft C, partially holted, substantially as shown.

In testimony that we claim the foregoing as

our own we affix our signatures in presence of two witnesses.

BENJAMIN HEYWOOD.
JOHN JONES.
